UNITED STATES PATENT OFFICE

2,584,621

PEBBLE HEATER

Martin A. Ryan, Bartlesville, Okla., assignor to
 Phillips Petroleum Company, a corporation of
 Delaware

Application October 20, 1947, Serial No. 780,925

5 Claims. (Cl. 23—277)

1

This invention involves improvements in the construction of pebble heaters.

One object of this invention is to provide a pebble heater in which the top of the reaction chamber lies in a plane parallel to the angle of repose of the pebble content thereof.

Another object of the invention is to provide an adjustable means for varying the free space between the top of the reaction chamber and the pebble bed therein.

A more specific object of the invention is to provide an adjustable discharge spout for the restricted entrance of the reaction chamber having a discharge lip lying in the plane of the angle of repose of the pebble bed therein.

A still more specific object of the invention is to provide a removable discharge spout of this type.

Another object of the invention is to provide an improved and simple form of heat exchanger quencher by means of which the effluent gases from the reaction may be cooled immediately after removal from the pebble bed.

A more specific object of the invention is to provide means associated with the effluent gas outlets from the reaction chamber by means of which these gases may be quickly cooled below predetermined temperature.

A still more specific object of the invention is to provide means for use with a pebble heater operating as a high temperature cracking unit for hydrocarbon fluids to produce an olefin-rich cracked gas for quenching the gas below its critical temperature to prevent excessive polymerization of the olefin content thereof.

Another object of this invention is to provide the above improvements in combination.

Other and more detailed objects of the invention will be apparent from the following disclosure of the embodiments thereof illustrated in the attached drawings.

This invention resides substantially in the combination, construction, arrangement and relative location of parts, all as will be described in detail below.

In the accompanying drawings,

Figure 1 is a vertical, central, cross sectional view through the upper portion of a pebble heater showing the features of this invention applied thereto, with some parts in elevation; and

Figure 2 illustrates a modification of a detail of the structure of Figure 1.

While pebble heater units are employed in various processes they are frequently used in

2

the high temperature cracking of hydrocarbon fluids to produce a highly olefinic cracked gas. As is well known in the art, such units comprise two or more chambers arranged in vertical relation and connected by a constricted section or conduit. The upper chamber is employed for the purpose of preheating the pebbles before they pass through the constriction into the lower chamber which is the reaction chamber.

In the high temperature cracking of hydrocarbon fluids to produce olefin-rich cracked gas, it is essential that the residence time of the reactants in the reaction zone be controlled and limited, usually to a relatively short period of the order of 0.05 second or less. In addition, as is well known, in order to secure a maximum yield of olefins this process is carried out at a maximum temperature and a minimum pressure. The temperature of the effluent gas is of the order of 1500° F. As is well understood, the free space above the pebble bed of the reactor must be minimized and the cracked gas or reaction products be withdrawn from the high temperature reaction zone and cooled or quenched below the reaction temperature as quickly as possible. This objective is attained in part in this invention by providing means for reducing the amount of free space above the pebble bed and by subjecting the reaction products to cooling almost immediately after leaving the pebble bed.

Pebble heater operation, with which this invention is concerned, may be utilized in a variety of chemical processes and treatments in which extremely fast heating of the reactants and very rapid quenching of the reaction products are required. In carrying out this operation, the residence time of the reactants in the conversion zone is very short, in some cases it may be of the order of $1/100$ of a second. It is also imperative that the reaction products be withdrawn immediately from the high temperature zone and quenched to a temperature below the reaction level. In the cracking of ethane to produce ethylene the temperature in the conversion or reaction zone may well be in the order of 1800° to 1900° F. with a residence time of .01 to .03 second. In order to produce the maximum yield of ethylene by eliminating side reactions, such as polymerization, it is essential that the effluent cracked gas be rapidly quenched to a temperature below about 1000° F. and preferably to a temperature as low as 600° F. The apparatus disclosed in this invention per-

mits achievement of very short residence time by means of a specially designed reaction chamber in which the top wall or head lies at an angle such that it is parallel to the top of the pebble bed which is allowed to assume its natural angle of repose. As a still further improvement, means are provided to control the free space between the top of the pebble bed and the wall of the vessel thus making it possible to vary the residence time of the reactants in the conversion zone.

In some instances the reaction products have been rapidly quenched by direct injection of some fluid such as water or steam into the effluent line from the reaction zone. However, there are many cases where a direct quenching procedure cannot be tolerated. In high temperature hydrocarbon conversions, such as cracking and dehydrogenation, for example, the production of ethylene or acetylene which are to be separated from the reaction products by low temperature fractionation, the use of a direct quench is not desirable because of the extensive dehydration which would be required prior to the separation steps. In other chemical processes or syntheses, such as the production of HCN from ammonia and carbon monoxide, production of CS_2 by reacting hydrocarbon vapors with sulfur containing gases and other syntheses involving HF as a reactant, a direct quench cannot be tolerated because the reaction product may combine or react with the quenching material. The new quenching means disclosed in this invention makes it possible to conduct these processes in a pebble heater type apparatus, without undesirable side reactions, dilution of product with resulting separation difficulties and other disadvantages.

In Figure 1 a metallic reaction vessel 2 is provided with a refractory lining 1 which extends upwardly into a restricted conduit extension of a housing 20 to form a lining therefor having a restricted passage 5 therethrough. An insulating lining 21 is provided with a shoulder 21', as shown, upon which a shoulder throat member 23, likewise of highly refractory material, may rest with the aid of refractory shims 24 by means of which the length of the projecting lower end thereof may be varied. The lower end of the throat member is of conical form as illustrated at 23' and the inclination thereof is substantially that of the angle of repose of the pebble bed 4. It will be seen that by varying the thickness of the shims 24 the space between the top surface 6 of the pebble bed and the sloping refractory wall 7 can be varied to meet particular conditions. The top of reaction vessel 2 is inclined, and the insulating lining 1 is similarly inclined so that its inner face 7 will be substantially parallel to the face 6 of the pebble bed.

The top wall 7 obviously will be of conical form in the case of a cylindrical construction, and in accordance with this invention it lies at an angle such that it will be parallel to the top 6 of the pebble bed 4 which is allowed to assume the natural angle of repose of the pebbles. The angle of repose of the pebbles commonly used at the present time for this purpose generally lies between 30 to 40 degrees, and can be readily determined by experiment, and hence the angle of the top 7 of the vessel will be constructed to be approximately the same. The upper end of the vessel is provided with a heat insulated extension 20 forming a restricted con-

duit 5 through which the pebbles pass from the preheating chamber above (not shown).

It will be understood that the longer the throat member 23, that is the more it projects below the discharge end of the conduit 5, the greater will be the free space between the top wall of the reaction vessel and the top 6 of the pebble bed, and vice versa. Thus the free space thus formed can be adjusted and minimized to the most suitable size for particular operating conditions.

Overlying the sloping wall 7 forming the top of the reaction vessel is a flat metallic housing 27 which may be in the form of a collar extending continuously around the top of the vessel, or a pair of separate semi-circular housings as illustrated. As shown, it is provided with one or more cooling inlet conduits 27A and outlet conduits 27B by means of which a cooling gas or liquid can be forced therethrough at the desired rate. Extending all the way through this relatively flat housing is a metallic conduit 29 which opens into the reaction vessel and is welded or otherwise connected to the adjacent wall thereof. The tube 29 is provided with a series of radial vanes 28 on the interior and a plurality of circumferential vanes 30 on the exterior. The upper ends of the tubes 29 are provided with flanges or other connecting means and are connected to any suitable offtake pipe or manifold (not shown). It will be noted that the inner ends of the tubes 29 open through a tortuous path 25' into the free space above the pebble bed through refractory block 25 and discharge into the pipe or manifold (not shown) to which they are connected. It will be understood therefore, that the effluent gases pass into the free space between the upper surface 6 of the pebble bed 4 and the wall 7 of the reaction vessel, and from 40 there directly into and through the tubes 25' and 29 substantially immediately after they issue from the pebble bed. In passing through the conduits 29 they are in heat exchange relation with the cooling fluid surrounding these tubes, 45 so that they lose heat rapidly by conduction through the metal wall of the tubes 29. The internal vanes 28 and the external vanes 30 aid in effecting a rapid heat transfer from the hot effluent unsaturated, or perhaps olefin-rich 50 gases to the cooling fluid passing through the housings 27. Thus the gases issue from 29 into the manifolds (not shown) at temperatures below the critical temperature for the reaction involved minimizing, in the case of the olefin-rich 55 gases, excessive polymerization thereof in the case of acetylene, the formation of carbon black, and in the case of other products, other well known undesirable side reactions. As the cooling need only be to 600° F. to 1000° F., depending on what side reaction is to be prevented, it is preferred to use a coolant in 27 around 60 vanes 30 that is selected as suitable for use at such temperatures. While, of course, water and other liquids that vaporize, or gases or vapors 65 can be employed, it is preferred to use molten salts, or molten metals that preferably do not vaporize at the temperatures involved, although ones that do vaporize can be used. Other coolants such as diphenyl or other high temperature 70 resistant substances may be used.

As illustrated the heat exchanger housings 27 in this case are in the form of two separate members of the required circumferential length with respect to the top of the reaction vessel, and 75 each having one or more tubes 29 extending

therethrough. To facilitate construction the tubes 29 are welded to plates 29' which in turn are welded into similarly shaped openings in the inclined wall in the top of the reaction vessel as shown. At the lower end the tubes 29 pass through openings in the lower walls of the housing 27 and are welded thereto. At the upper end they are welded to plates 29'' through which they pass and which in turn are welded into similarly shaped openings in the top wall of the housings 27. As previously mentioned tubes 29 are provided with a series of internal radial vanes 28 and external circumferential vanes 30 to increase the heat absorbing reaction thereof.

In the construction illustrated the insulating lining 21 for the reaction vessel is shaped in the region of the inlet ends of the tubes 29 to receive removable highly refractory insert members 25 which have the non-linear passages 25' therethrough establishing communication between the free space above the pebble bed and the interior of the tubes 29. In the form illustrated in Figure 2 the passages 25 are merely offset sufficiently so that the area of the top of the pebble bed opposite the entry end thereof is not directly exposed to too large a dark space. As those skilled in the art will understand under these conditions the exposure of the hot pebble bed to a cool dark space will cause the hot pebbles exposed thereto to radiate heat at an excessive rate, causing an undue cooling of the portion of the pebble bed exposed to the dark space. In some cases cooling may be carried to a point below the proper reaction temperature, possibly causing undesired reactions and undue deterioration of the pebbles in that region. The members 25 are made removable in the event that it may become desirable to replace or change them for any reason. The housings 27 are provided with inlets 27A and outlets 27B for the cooling fluid. One of the most efficient ways of making passage 25' tortuous enough to hide metal surfaces 28 from pebbles 6, and yet be short, is to make it helical.

When desired, the inserts 25 may be provided with several passages arranged, for example, in a manner similar to that illustrated in Figure 2, or in the form of helixes to minimize the dark space effect previously explained. Thus, a plurality of passages 25A are illustrated in Figure 3 as being offset or of helical form to accomplish this objective. In some cases the longitudinal vanes 28 may be given a helical or distorted form. Thus, for example in the arrangement of Figure 1 if they are thus formed the cool dark space effect will be minimized.

The construction of Figure 2 is practical in that the strains due to temperature differentials encountered in the heat exchanger are minimized by reason of the welded construction for mounting the tubes 29 and the fact that only one tube in each case may be used freeing the heat exchanger for movement to ease the strains. With suitable precautions in this respect more than one tube 29 can be used in the housing 27.

For emphasis it will be again noted that by means of the construction illustrated the residence time of the reactants in the reaction vessel

is reduced to a minimum and is subject to control for that purpose.

From the above description it will be apparent to those skilled in the art that the subject matter of this invention is capable of some variation without departure from the novel subject matter thereof. I do not prefer therefore to be limited only as required by the claims granted me.

10 What is claimed is:

1. In a vessel for effecting heat exchange between up-flowing gases and down-flowing pebbles, the combination comprising a vessel having a top wall, a restricted pebble supply conduit projecting into said vessel through said top wall, an effluent gas takeoff conduit mounted on said top wall, a circulatory liquid housing surrounding said conduit, internal radial vanes on said conduit, and external circumferential vanes on said conduit and within said housing.

2. In the combination of claim 1, a throat member formed with a flange around its external circumference, the flange forming a collar for supporting said throat member in position in 25 the reactor, the level of said throat member being adjustable by the inclusion of shims between the collar and the reactor top.

3. In the combination in accordance with claim 1, the throat member being formed with a 30 discharge opening tapered to define essentially the angle of repose for the bed of pebbles.

4. In a pebble reactor, the combination comprising a reaction vessel, said vessel having a conical top wall, a restricted heated pebble supply conduit at the apex of said vessel and projecting into said vessel to form a pebble bed having a conical top surface and to form a free space between said conical top wall and bed top surface of substantially uniform height at every 40 point, an effluent gas take-off conduit mounted on said conical top wall, a circulatory liquid housing surrounding said conduit, internal radial vanes on said conduit and external circumferential vanes on said conduit and within said housing.

5. In the combination of claim 4, an inlet member for said conduit comprising a refractory member having a tortuous path therethrough, said refractory member minimizing the cool dark space effect.
